United States Patent Office

Des. 205,262
Patented July 12, 1966

205,262

SURVIVAL HEATER

Ewald J. Kimm, Dayton, Ohio, assignor to United Aircraft Products, Inc., Dayton, Ohio, a corporation of Ohio

Filed Oct. 19, 1965, Ser. No. 87,598

Term of patent 14 years

(Cl. D81—10)

FIG. 1 is a view in perspective of a survival heater embodying my new design, the guard surrounding the heater bowl being shown extended;

FIG. 2 is a top plan view of the survival heater, the guard being shown collapsed;

FIG. 3 is a bottom plan view; and

FIG. 4 is an end view, taken from the open end of the U-shaped tank, the opposite end showing the closed end of the tank and the sides showing the sides of the tank.

I claim:

The ornamental design for a survival heater, as shown and described.
